by E. E. Masson, Attorney.

UNITED STATES PATENT OFFICE.

JONAS L. KNOLL, OF LEBANON, PENNSYLVANIA.

WASHING-MACHINE.

SPECIFICATION forming part of Letters Patent No. 530,277, dated December 4, 1894.

Application filed June 10, 1893. Serial No. 477,219. (No model.)

To all whom it may concern:

Be it known that I, JONAS L. KNOLL, a citizen of the United States, residing at Lebanon, in the county of Lebanon, State of Pennsylvania, have invented certain new and useful Improvements in Washing - Machines, of which the following is a specification, reference being had therein to the accompanying drawings.

10 This invention relates to that class of washing machines wherein the cleansing of the clothes is effected by means of a vibrating slatted rubber and slatted end racks in the interior of the suds-box and connected to the rubber, to receive therefrom a reciprocating motion to agitate and press the clothes placed between said rubber and racks, to facilitate the removal of the dirt therefrom, and substantially as shown in Patent No. 406,918, granted

20 to me July 16, 1889.

The objects of my improvements, are, first, to improve the construction of the bottom of the suds-box to render it lighter, stronger and more lasting; second, to facilitate the prompt removal of the rubber and racks from the suds-box, to divide the weight of that class of machines into substantially two halves and thus facilitate its handling by weak persons; third, to provide the outer ends of the rack 30 arms with outwardly projecting pins to slide in grooved guides secured to the suds-box, and their inner ends with wavy-serrated slots to receive their operating pin, and with peculiarly notched latches to retain each rack-arm adjustably connected to said operating pin.

Other objects and details of construction will be hereinafter described and specifically set forth in the claims.

40 In the accompanying drawings Figure 1 is a longitudinal vertical section of a washing machine constructed in accordance with my invention. Fig. 2 is a plan view of the same with the cover and the upper part of the handles removed, and the side strips of the top turned up on edge to show the grooved guides and arm connections for the racks. Fig. 3 is a transverse vertical section of a portion of the machine through the center 45 thereof. Fig. 4 is a perspective view of one of the grooved guides for the racks. Fig. 5 is a perspective view on a larger scale of one

of the bearings for the journals of the rubber, and a portion of the frame carrying said bearing. Fig. 6 is a perspective view of the 55 inner end of one of the rack-arms of the outer pair, said rack arm having pivoted to its extreme end a latch having in its under side notches wider at their upper than at their lower portion, the sides of said notches being 60 in the form of double beveled spear-heads. Fig. 7 is a perspective view of the inner end of one of the rack-arms of the inner pair. Fig. 8 is a perspective view of one of the latches to engage with the inner pair of rack- 65 arms. Fig. 9 is a perspective view of a portion of the outer face of one of the end-frames of the rubber showing the flattened or oval stud-pivot thereof and the pivot-pin for the rack-arms. Fig. 10 represents on a large scale 70 a portion of one of the sides of the suds-box and of the sheet metal bottom thereof secured thereto in accordance with my invention.

In said drawings A represents the suds-box supported upon legs B and provided with an 75 outlet a for drawing off the water. The stationary portion A² of the top, at one end of the box is slightly inclined and may be used as a soap-receptacle. It has two perforations a³ therein to receive the legs of a wringer. 80 The stationary portion A³ of the top at the opposite end of the box has cleats a⁴ secured to its under side to receive one end of the cover A⁴, the opposite end thereof resting upon the opposite portion A² of the top. To 85 the sides of the box adjacent to their upper edge, wood-straps a⁵ are hinged to permit them to be swung outwardly when it is desired to take off all the movable inner parts of the machine to render the suds-box suitable for rinsing clothes.

The bottom of the suds-box is not made of wood, as said material is objectionable on account of its shrinkage during dry weather, and undue swelling when the box is filled 95 with hot suds or water, causing the sides to be pushed apart. In this machine the bottom A⁵ consists of sheet-metal, preferably zinc secured to the bottom edge of the ends and sides A of the box by means of nails a⁶. Fig. 100 10, driven at suitable distances apart through said zinc and into the bottom edge of said ends and sides. Said bottom edge is preferably slightly beveled outwardly, and to add

to the retaining property of the nails and to the liquid retaining capacity of the fastening, the edge of the sheet metal is flanged and forced into the edge of the lumber as at a^6 by 5 means of a suitable calking chisel. To the inner surface of the box are secured the bearings a^7 for the journals or stud-pivots d^4 of the rubber D. Said rubber consists of two metallic disks or rings d having a series of 10 slots or pockets on their inner side to receive the ends of the slats d^2 extending from one ring to the other. Said rings are united together by means of a bolt d^3 in the center thereof. An arm D' extends diametrically 15 across the ring from its lower periphery to its upper cross bar d' and projects upward on top of said cross bar. To the upper ends of said arms are secured the side pieces D² of the handle D³ said side pieces passing through 20 slots between the cover A⁴ and the hinged strips a^4 of the suds-box. To permit the rings d to withstand the powerful traction of the bolt d^3 and nut thereon, the portion of the arm D' within the ring is provided with an 25 arched rib d^5 on each side of the bolt d^3 , and the cross bar d' is also provided with an arched rib. To support the slats d^2 against external pressure a substantially cylindrical block d^6 is placed in the center of the rubber and each 30 slat is pinned thereto, dividing the interior of the rubber into two equal chambers.

The racks E and E² operated in connection with the rubber have projecting outwardly from their upper ends pins e by which they 35 are supported; said pins being received in grooved guides F secured to the inner face of the sides of the suds-box adjacent to the top thereof. In the top rib of each of said guides adjacent to the inner end thereof there is a 40 groove f for the passage of the pins e at the time that the racks and rubber are placed within the suds-box before doing a washing, or at the time said parts are removed from the suds-box. The racks E² have projecting 45 inwardly from their upper ends arms E³, and within the ends of said arms peculiarly shaped slots e⁸ are formed. The upper edge of each of said slots has wavy serrations to form three (although it may have more) shallow pockets e⁴ 50 either one of which is intended to receive in engagement a pin d⁷ projecting outwardly from the face of the arms D' of the frame of the rubber D. To securely retain the pin d⁷ in engagement with either one of the pockets e⁴, each 55 arm E³ has teeth e⁵ projecting from its upper edge to obtain seats e⁶ alongside of said teeth, and with either one of said seats, a latch g is made to engage. Said latch is mounted upon 60 and made to project inwardly from the side 65 of the arm G that has in its inner end a round hole g² of slightly larger diameter than the pin d⁷ in which said pin is received as a pivot for the latch. Said latch has a bent upper lip g³ by which it can be pushed outwardly 70 and lifted by the operator to adjust its position in one of the seats e⁶; but to retain the latch g normally in engagement with the seats

e⁶ the latch is provided with a groove g⁴ in its side and thereunder, for engagement with a rib e⁷ on the outer face of the arm E³. The 75 body of the arm E³ having no pivot hole therethrough is not weakened by the removal of any metal from said body.

The racks E have projecting inwardly from their upper ends arms E⁴, and within the ends 80 of said arms, the peculiarly shaped slots e⁸ are also formed having wavy serrations to form shallow pockets e⁴ either one of which is intended to receive the pin d⁷ in engagement. To securely retain said pin d⁷ in engagement with either one of the pockets e⁴ and e⁸ each arm E⁴ has pivoted to its extreme 85 end at k a latch K having in its under side notches k² that may be called of dovetail form, being wider in their middle than in their lower portion, the sides of said notches being in the form of pendent double beveled spear head partitions k³ that are more reliable than parallel sides to remain in engagement with the pin d⁷ when the parts are wet 90 with slippery soap suds. To prevent the latch K from being swung more than an arc of about one hundred degrees upon its pivot, the end of said latch adjacent to said pivot has a projection k⁴, to strike against a lug e⁸ 95 projecting from the side of the arm E⁴. Said arm has also a lug e⁹ on the side thereof to keep the latch from being revolved too far in the opposite direction while out of engagement with the pin d⁷. By having the pivot 100 k for the latch K at the outer end thereof in place of at any point on the arm E⁴ between the slot e⁸ and the rack E, said arm E⁴ is not weakened by the removal of any metal from its body to form the pivot-hole.

105

To prevent the rubber D or its pivot pins d⁴ from jumping out of the bearings a⁷, when the operator gives too great an oscillation to said rubber, or when shipped to uninitiated operators with the side pieces D² of the handle in a position nearly parallel to the top of the suds-box, the pins d⁴ have their sides flattened, and the upper portion or opening a⁸ to the bearing a⁷ is narrower than the interior of said bearing. The width of the 110 opening a⁸ is substantially equal to the width of the flattened portion of the pin d⁴, while the diameter of the interior of the bearing a⁷ is substantially equal to the vertical diameter of said pin d⁴. Above the opening 115 a⁸ the sides of the bearing are outwardly flaring at a⁹ to permit the operator to easily direct the pins d⁴ within their bearings, while 120 replacing the rubber D and the racks E E² connected thereto, within the suds-box.

125

To retain the slotted end of the pair of side arms E³ and particularly the slotted end of the pair of side arms E⁴ of the castings of the racks sprung toward the rubber D, and at the same time retain the ends of the slats h² h³ within their pockets in said rack-castings, each of said castings has a perforated lug h⁴ projecting from its inner edge, toward the rubber, and bolts or headed rods h⁵ are 130

received into and retained by said lugs. The slats h h^2 are wider than those shown in my Patent No. 406,918, to render them stronger, and are provided on their inner side with a groove h^6 having a beveled face and a rectangular edge to properly operate upon the clothes placed between them and the rubber.

By having the rack arms connected to the rubber in a substantially permanent manner, the operator by lifting said rubber out of the suds-box removes also at once the racks from said suds-box, leaving the latter free of incumbrances, to clean it out, adapt it for rinsing clothes, and reduces its weight about one half.

Having now fully described my invention, I claim—

1. In a washing machine the combination of a suds-box, bearings a^7 centrally secured to the sides of said box and having a top opening to said bearing narrower than its interior, a cylindrical rubber D having slat-retaining cast ends provided with arms D' , and pins d^4 outwardly projecting from said arms and having their sides flattened, their short diameter corresponding with the narrow opening of the bearing and their long diameter corresponding with the interior of said bearing substantially as described.
2. The combination of a suds-box, a cylindrical rubber pivoted in bearings secured to the sides of said box, the end castings of said rubber having arms D' provided with pins d^7 , two racks having arms, each arm provided with a slot in its inner end adjustably connected with the pin d^7 , and a pin e outwardly projecting from its outer end, with grooved guides F receiving the pins e and secured to the sides of the suds-box substantially as described.

3. The combination of a suds-box, a cylindrical rubber pivoted in bearings secured to the sides of said box, the end castings of said rubber having arm D' provided with pins d^7 , a rack E having arms E^4 provided with a wavy-serrated slot in its inner end, a latch K pivoted to the extreme end of said arms and having notches separated by double beveled spear-head partitions between said notches with a rack E^2 having slotted arms E^8 adjustable upon the pins d^7 the slots in said arms having pockets e^4 substantially as described.

4. The combination of a suds-box, a cylindrical rubber pivoted in bearings secured to the sides of said box, the end castings of said rubber having arms D' provided with pins d^7 , a rack E^2 having arms E^8 provided with a wavy-serrated slot in its inner end and teeth e^5 upon its top, a latch g pivoted upon the pin d^7 and in engagement with one of said teeth, and a rack E having slotted arms adjustable upon the pins d^7 substantially as described.

5. The combination of a suds-box, a cylindrical rubber pivoted in bearings secured to the sides of said box, the end castings of said rubber having arms D' provided with pins d^7 , racks, and horizontal rack arms adjustably connected at one end with said pins d^7 and at the other with supporting pins e , with grooved guides F for said pins e , said guides being secured to the suds-box above said racks substantially as described.

In testimony whereof I affix my signature in presence of two witnesses.

JONAS L. KNOLL.
